United States Patent Office

Des. 186,664

Patented Nov. 17, 1959

186,664

CARD PROVING MACHINE

James J. La Due and Walter S. McCormick, Jr., Poughkeepsie, N.Y., assignors to International Business Machines Corporation, New York, N.Y., a corporation of New York

Application April 30, 1959, Serial No. 55,716

Term of patent 14 years

(Cl. D26—5)

FIG. 1

Des. 186,664

PAGE 2

FIG. 2

FIG. 3

Fig. 1 is a front perspective view, showing our new design, of a card proving machine;

Fig. 2 is a rear perspective view; and

Fig. 3 is a right side elevation view thereof, the left side being plain and unornamented.

The grill is continuous across the back panel of the machine between the fragmentary portions shown.

We claim:

The ornamental design for a card proving machine, substantially as shown and described.
